(57) **CLAIM**

The ornamental design for a mixing element for a beverage shaker, as shown and described.

DESCRIPTION

FIG. 1 is a top front left perspective view of a mixing element for a beverage shaker showing my new design.

FIG. 2 is a top plan view thereof.

FIG. 3 is a left side elevation view thereof.

FIG. 4 is a bottom plan view thereof.

FIG. 5 is a right side elevation view thereof.

FIG. 6 is a back elevation view thereof; and,

FIG. 7 is a front elevation view thereof.
